ASH STORAGE AND CONVEYING APPARATUS

Frederick L. Stokoe, Chicago, Ill.

Application November 2, 1942, Serial No. 464,310

7 Claims. (Cl. 110—171)

My invention relates to ash storage and conveying apparatus. More specifically it relates to apparatus for storing and conveying solids or granular material and the like, particularly ash and refuse produced by burning coal, coke, and combustible material in various types of furnaces, especially in connection with steam boiler plants.

In storage and conveying systems of this character it is customary to maintain a flowing stream of water along the bottom of a hopper or chamber into which ash, in a dry or fluid state, is continuously falling and being carried away with the stream of water. Such a system is wasteful of power in that it requires a constant pumping to supply the water and pressure necessary, is uneconomical to operate, and allows air to enter the hopper or chamber which communicates directly with the furnace of the boiler, thereby reducing the efficiency of the boiler due to the presence of an uncontrolled supply of air in excess of that required for proper combustion. The continuous operation of the system allows no period of time for repairs to any part of the system. The presence of water vapors produced by the hot ash falling into water tends to lower the efficiency of the furnace and produces corrosion of metals in other parts of the boiler equipment.

Another method is used in which the material is allowed to accumulate in a hopper or chamber provided with a sloping bottom which slopes uniformly upwardly from the discharge opening in the hopper to the rear of the hopper. After a desired quantity of ash has been accumulated, it is customary to discharge a stream of water up the sloping floor until it strikes the ash and then returns by gravity down the sloping floor, carrying ash with it through the discharge opening of the hopper. The sloping floor is wasteful of hopper space, uneconomical in construction, is limited in effectiveness in removing large pieces of ash or slag, and requires a large volume of water to remove the ash.

The stream of water with its consequent sprays, when brought into contact with the hopper walls and floor, produces spalling and destruction of the hopper lining which is at a high temperature. Due to the necessity of keeping the discharge door fully open to allow the water jet, which is located outside the hopper, to discharge the water up the sloping floor, large quantities of air enter the hopper and produce a marked lowering of efficiency of the boiler. Attempts have been made to protect the floor against the intense heat by placing water sprays in the side walls of the hop-

per. Due to the high temperature in the hopper, this spraying produces steam which enters the furnace above the hopper and lowers the efficiency of the furnace and also produces disintegration of the lining of the hopper and starts corrosion of steel plates in the auxiliary boiler equipment, due to the union of the water vapor and sulphur in the gases of combustion.

Among the objects of my invention are to provide an apparatus which allows a longer storage period, provides a greater storage capacity, is economical to construct and operate, and increases the rate of discharge of material from the hopper by utilizing the entire available energy of high pressure jets of water. Sufficient energy is always available to discharge large lumps of ash or slag by controlling the water supply to the hopper, thus making it unnecessary to remove the large pieces manually.

20 To prevent air infiltration into the hopper during the period of ash discharge, which infiltration reduces furnace efficiency, provision is made for the automatic opening of the discharge door a sufficient distance only to allow the passage of water and ash through the opening. This is accomplished by allowing the pressure of water and ash to push the door open in proportion to the quantity of water and ash passing through the opening.

30 To protect the floor of the hopper from destruction due to excessive heat and the rapid cooling of the walls and floor, enclosed fluid containers are used to receive and cool the ash. The under surface of the container protects the floor beneath it from becoming overheated. The shape of the container confines the water from the jets and prevents it from touching the hot side walls of the hopper which could cause disintegration of the hopper lining and floor.

40 At the discharge opening in the hopper wall the lining is protected by means of a fluid container in which a cooling medium circulates and carries away the heat at that section of the wall. This fluid container also keeps the discharge door sufficiently cool to prevent warping of the door, thus preventing air infiltration into the hopper due to warpage of the door.

50 Protection is also given the operator against flashes of hot gases passing through the discharge opening as the discharge door is opened only a sufficient amount to accommodate the ash and water.

Other objects and advantages of the invention will be apparent from the description and claims.

In the drawings, in which two embodiments of my invention are shown.

Figure 1 is a plan view of the apparatus;

Fig. 2 is a front elevational view, parts being broken away and shown in section;

Fig. 3 is a vertical, transverse, sectional view on the line 3—3 of Fig. 2; and

Fig. 4 is a vertical, transverse, sectional view showing a somewhat different form of hopper bottom.

The construction shown in the drawings comprises an ash storage and conveying apparatus including portions of a water tube boiler, or boilers 1, an ash hopper or pit underneath the boilers 1 having front and rear walls 2 and 3, and a bottom 4 on which the ashes, etc., fall from the furnace, a plurality of longitudinally-spaced openings 5 in the front wall of the hopper adjacent the bottom of the hopper through which openings the ashes are ejected from the hopper, a sluiceway 6 extending along in front of the hopper below said ejector openings into which sluiceway the ashes are ejected from said openings, pressure-operated closures 7 for said openings, respectively, jet nozzles 8 for directing jets of water from the rear to the front of the hopper adjacent the bottom thereof and toward said openings for undermining and ejecting ashes which have fallen into the hopper, and manual means 9 operable from the rear of the hopper for manually controlling the opening and closing of said pressure-operated closure means 7.

In use, the ashes falling from the furnace pile up in the hopper until the hopper is so full that it is desirable to remove them. The attendant operates the levers 10 in the rear of the hopper to open the closure means 7 to the desired extent and turns on the jet nozzles 8, the water from which streams across the hopper toward the openings 5 adjacent the bottom of the hopper and undermines the pile of ashes and ejects them through the openings into the sluiceway 6, which carries them to the sump or other place of disposal.

The lining 11 of the hopper may be formed of any suitable refractory material suitable for withstanding heat and other conditions to which it is subjected. This may be surrounded by a layer of suitable insulation 12 enclosed in a metal sheathing or wall 13. The hopper may be provided with a suitable number of "poke" openings 14 through which a poker or the like may be inserted for loosening the ashes or scraping the interior. The upper openings 14 may be provided with suitable opening and closing means 15, operable by the attendant standing on the floor 15a. The hopper may also be provided with any suitable number of sight openings 16, each covered with a glass closure 17 through which the contents of the hopper may be seen. The rear wall of the hopper is recessed, as indicated at 18, to provide clearance for the jets and to prevent the ashes which fall into the hopper from clogging up the ends of the jet pipes 8. The hopper may be provided with suitable openings 19 at the end through which access may be had to the interior of the hopper.

The bottom of the hopper may be made up of a plurality of trough-like sections 20 extending transversely of the hopper from one side wall to the other. These trough-like sections tend to confine the jets of water to a direction transverse to the hopper and directed toward the openings in the front wall, one opening being placed opposite the discharge end of each trough-like sec-

tion. These trough-like sections may be made of any suitable material capable of withstanding the conditions to which the sections are subjected.

In order to prevent the sections from getting excessively hot from the effects of the hot ashes and cinders, cooling means are provided. For this purpose, the walls of the trough-like sections are made hollow, as indicated at 21, forming semi-cylindrical chambers through which cooling water may be circulated. The passages 5 through the front wall, through which the ashes and water are ejected, are surrounded by hollow annular castings 22 through which cooling water may be circulated to prevent the walls of the openings from becoming too hot.

The sluiceway 6 into which the ashes are ejected may extend along in front and below the lower edge of the front wall of the hopper. The bottom and front of the sluiceway may be lined with any suitable material capable of withstanding the conditions to which it must be subjected.

In order to prevent ashes, water, and steam from escaping into the atmosphere when the closures are opened, each opening is provided with a housing member or discharge chamber 23 which encloses the closure member 7 and affords communication between the interior of the hopper and the sluiceway 6 when the closure members 7 are opened. Each of these housing members 20 may be provided with a door 24 affording access to the closure member 7 when desired for inspection, repairs, and the like.

Each pressure-operated closure member 7 comprises a door mounted on a rock shaft 25 and movable from a position in which it seals the opening 5 to a position in which it allows the discharge of the ashes and water. For manually opening and closing each of these doors, a lever 10 is provided at the rear of the hopper pivotally mounted at 26 and pivotally connected at 27 with a connecting link 28 which extends through a tubular opening 29 adjacent the bottom of the hopper and is pivotally connected at 30 with a rock arm 30a secured to the rock shaft 25 on which the pivoted closure member 7 is mounted.

In order to bias the closure member 7 to closing position, a counterweight 31 is provided mounted on a rock arm 32 secured to the rock shaft 25 on which the closure member 7 is mounted. In order to counteract to some extent the closing tendency or bias of the counterweight 31, the operating lever 10 is provided with a somewhat lighter counterweight 33. By referring to Fig. 3, it will be seen that the closing action of the counterweights is most effective at and near the closed position of the closure member 7 and that their closing effect becomes less as the opening increases, due both to the change in angle of the counterweight arm 32 and to the change in angle of the lever 10. The counterweights, arrangement of pivots and other features are designed so that the forces tending to close the closure member 7 will be suitable for opposing the pressure of the ashes in the hopper and the pressure due to the fluid jets so that the door will automatically adjust itself to the desired position of opening, depending on the pressure of the ashes and the pressure of the liquid.

Suitable means may be provided for opening and closing the jet nozzles designed so that the valves may be opened singly or collectively.

In Fig. 4 is shown a somewhat different construction of hopper bottom. The upper hopper construction, the closure 7, and the sluiceway 6 may be substantially as shown in Fig. 3. In the

form of Fig. 4, however, the hopper bottom is made up of stepped sections with a jet nozzle for each step of a section. The front section is shown as a substantially horizontal trough 34 and the rear section as an inclined trough 35. A stepped formation is provided between the two troughs affording a location for a jet nozzle 8, another nozzle 8 being provided at the rear of the trough 35. Such a construction may be desirable under certain conditions as it allows a jet of water to be applied to the pile of ashes at a point intermediate the front and rear walls. Furthermore, the slight inclination of the rear trough section facilitates the discharge of the water and ashes.

In Fig. 4 the door 7 is shown open, in order to bring out a feature of construction designed to prevent the act of discharging ashes and water from impairing the seating action of the closure. As shown, the door is mounted for limited pivoted movement at 36 on the rock arm 37 so that the seating flange 39 of the door can adjust itself to the seat 40 on the door frame 38. Excessive pivotal action of the door on the rock arm is prevented by the stops 41 which are engageable with the rock arm 37.

In order to prevent the discharge of ashes and water from impairing the seating surface 39, a shield or baffle plate 42 is secured to the door so that when the door is opened the shield 42 will in general protect the seating surface 39 from the impact of the ashes and water.

It will be seen that the construction disclosed allows a long storage period, provides a large storage capacity, is economical to construct and operate and effects a high rate of discharge of material from the hopper by utilizing the energy of high pressure jets of water. Air infiltration into the hopper during the period of ash discharge is prevented by the automatic opening of the discharge door 7 a sufficient distance only to allow the passage of water and ash through the opening.

The floor of the hopper is protected from destruction due to excessive heat and the rapid cooling of the walls and floor by the enclosed fluid containers 20 which receive and cool the ash. The under surface of the container protects the floor beneath it from becoming overheated. The shape of the container confines the water from the jets and prevents it from touching the hot side walls of the hopper which could cause disintegration of the hopper lining and floor.

At the discharge opening in the hopper wall the lining is protected by means of a fluid container 22, in which a cooling medium circulates and carries away the heat at that section of the wall. This fluid container also keeps the discharge door sufficiently cool to prevent warping of the door, thus preventing air infiltration into the hopper due to warpage of the door.

Protection is also given the operator against flashes of hot gases passing through the discharge opening as the discharge door 7 is opened only a sufficient amount to enable the passage of the ash and water.

Some of the advantages of designing the means for operating the closure 7 and the means for controlling the supply of liquid to the jets so that they are accessible to and operable by an attendant on the side of the hopper opposite the ejection openings, are that the streams of liquid and the ashes carried thereby are driven away from the operator so that the escape of dust, steam, moisture, etc., is in general from the side of the hopper remote from the attendant and that the

glass-covered sight openings in the rear wall of the hopper are not so apt to get covered with a deposit of ashes and moisture as they would be if they were near the discharge openings for the ashes.

Further modifications will be apparent to those skilled in the art and it is desired, therefore, that the invention be limited only by the scope of the appended claims.

Having thus described my invention, what I claim and desire to secure by Letters Patent is:

1. An ash storage and conveying apparatus comprising a substantially horizontal floor, a hopper having front and rear walls and an elongated bottom of substantially greater length than width extending longitudinally of and between said walls, on which bottom the ashes fall, said front wall having a plurality of longitudinally spaced discharge openings therethrough adjacent the bottom of the hopper, said bottom having a plurality of transversely extending channels therein extending substantially across said bottom leading to said openings, respectively, operable closure means for each opening, means for maintaining cooling fluid closely adjacent the walls of said channels and preventing the cooling fluid from entering the hopper, means for injecting fluid into said hopper above said floor into and along said channels in the direction of the openings to cause it to flow substantially the length of said channels to eject the deposit of ashes through said openings, a sluice channel into which the ashes are ejected through said opening, and a housing for each closure providing an enclosed passage from the opening to said sluice channel, said housing being provided with an opening having a second openable closure affording access to said first closure.

2. An ash storage and conveying apparatus comprising a hopper having immovable refractory front and rear walls having a relatively smooth inner surface, and a bottom wall comprising a plurality of channel sections disposed in parallel side-by-side relation and extending from the rear wall to the front wall, said front wall having a plurality of openings therethrough, one for each channel for the ejection of ashes from the channel sections, each channel section having means providing a relatively thin covering of cooling water over the major portion of said channel section.

3. An ash storage and conveying apparatus comprising a hopper having immovable refractory front and rear walls having a relatively smooth inner surface, and a bottom wall comprising a plurality of channel sections disposed in parallel side-by-side relation and extending from the rear wall to the front wall, said front wall having a plurality of openings therethrough, one for each channel for the ejection of ashes from the channel sections, each channel section having means providing a relatively thin covering of cooling water over the major portion of said channel section and having means for each channel section adjacent the rear wall for directing a stream of fluid toward the opening in the front wall for ejecting all of the ashes in said channel through said opening.

4. An ash storage and conveying apparatus comprising a hopper having immovable refractory front and rear walls having a relatively smooth inner surface, a bottom wall comprising a plurality of channel sections disposed in parallel side-by-side relation and extending from the rear wall to the front wall, said front wall having

a plurality of openings therethrough, one for each channel for the ejection of ashes from the channel sections, each channel section having means providing a relatively thin covering of cooling water over the major portion of said channel section, and a plurality of closure means, one for each opening.

5. An ash storage and conveying apparatus comprising a hopper having immovable refractory front and rear walls having a relatively smooth inner surface, a bottom wall comprising a plurality of channel sections disposed in parallel side-by-side relation and extending from the rear wall to the front wall, said front wall having a plurality of openings therethrough, one 10 for each channel for the ejection of ashes from the channel sections, and having means for each channel section adjacent the rear wall for directing a stream of fluid toward the opening in the front wall for ejecting all of the ashes in said channel through said opening, a plurality of closure means, one for each opening, and means 15 operable by an attendant adjacent the rear wall for initiating the action of the jet means and causing the opening of said closure means.

6. An ash storage and conveying apparatus comprising a hopper having immovable refractory front and rear walls having a relatively smooth inner surface, a bottom wall comprising a plurality of channel sections disposed in parallel side-by-side relation and extending from

the rear wall to the front wall, said front wall having a plurality of openings therethrough, one for each channel for the ejection of ashes from the channel sections, and having means for each channel section adjacent the rear wall for directing a stream of fluid toward the opening in the front wall for ejecting all of the ashes in said channel through said opening, a plurality of closure means, one for each opening, and means 5 operable by an attendant adjacent the rear wall for initiating the action of the jet means and causing the opening of said closure means, said closure opening means comprising transmission means extending underneath said channels from the attendant operable means to said closure means.

7. An ash storage and conveying apparatus comprising a hopper having immovable refractory front and rear walls having a relatively smooth inner surface, a bottom wall comprising a plurality of channel sections disposed in parallel side-by-side relation and extending from the rear wall to the front wall, said front wall having a plurality of openings therethrough, one 10 for each channel for the ejection of ashes from the channel sections, a plurality of closure means, one for each opening, and cooling means comprising a plurality of annular members, one for each opening, each annular member surrounding an opening and lying within the front wall.

FREDERICK L. STOKOE.
